UNITED STATES PATENT OFFICE.

EMIL BOULANGER, OF ST. LOUIS, MISSOURI.

WATERPROOF WOVEN SNARE-STRING FOR DRUMS.

SPECIFICATION forming part of Letters Patent No. 480,063, dated August 2, 1892.

Application filed May 10, 1892. Serial No. 432,492. (No model.)

To all whom it may concern:

Be it known that I, EMIL BOULANGER, of the city of St. Louis and State of Missouri, have invented certain new and useful Improvements in Snare-Strings for Drums, of which the following is a full, clear, and exact description, reference being had to the accompanying drawings, forming a part hereof.

My invention relates to improvements in snare-strings for drums; and it consists in the novel arrangement and combination of parts, as will be more fully hereinafter described, and designated in the claims.

In the drawings, Figure 1 is a top elevation of the snare-head of a drum, showing the relative position of the snares. Fig. 2 is a detail sectional view of an improved snare-string, the same being my complete invention. Fig. 3 is a transverse section of a snare-
20 string, showing the relative position of the core, strands, and outer coating. Figs. 2 and 3 are enlarged views in order to show clearly my construction of a snare-string.

The object of my invention is to construct a snare-string which by reason of its smoothness of surface imparts a clear and distinct tone to the drum.

My device, being constructed and finished as will be more fully hereinafter described, 30 has none of the rough surfaces which are common to other snare-strings and which naturally tend to deaden the tone of the drum.

Referring to the drawings, 1 indicates the rim or shell of an ordinary drum having a 35 snare-head 2 and a number of snare-strings 3.

4 is a snare-string constructed after my method having a central core 5, said core being made of a suitable piece of twine or cord and having plaited or twisted around said core 5 a 40 number of strands 6, preferably made of fibers of sea-weed or similar fibrous material. The core 5, with the strands 6 plaited around same, is treated with a weatherproof material 7, which fills up all the pores of the strand. The 45 strand, after being treated with a weatherproofing material, is drawn through a die or any other suitable appliance to make its outer surface 8 perfectly smooth and free from all obstructions. This strand is again treated 50 with another coating 9 of the weatherproof-

ing material and subjected to the same process as before mentioned and is again in a perfectly-smooth state. The core 5, with strands 6 and coatings of weatherproof material 7 and 9, is now subjected to a coat of 55 shellac 10 or some equally resinous substance and is again drawn through a circular die, thus giving the snare-string complete a perfectly-smooth outer surface for the purpose set forth in my description of the object of 60 the invention. The core and fibers plaited thereon may be treated with any desirable number of coatings of weatherproof material or varnish without affecting the original idea and operation of my invention. 65

Having fully described the mechanical parts and construction of my invention, I will now proceed to state my reasons for claiming the improvements.

The drawing of the strand through the die 70 insures a perfectly-smooth outer surface.

The weatherproofing material is a very important feature of my invention. When ordinary snare-strings are exposed to the damp, they immediately loosen their tension, thus 75 spoiling the tone of the drum. In addition to this fact, they not only loosen, but the tension of each string is different, thus necessitating the adjustment of each string separately. A snare-string constructed after my 80 method prevents this change in the tension of the string, as the compound used is impervious to the effect of dampness.

In addition to the advantage gained by the use of this weatherproofing compound, the 85 production of a snare-string having a perfectly smooth and even outer surface is an important factor in the construction of the drum, as it imparts to the same a clear tone, which is very desirable, and the string after 90 this preparation never becomes what is called "stringy" or "fuzzy."

Having fully described my invention, what I claim is—

1. As a new article of manufacture, a snare-string comprising a number of strands of fibrous material and a weatherproof compound applied thereto and all compressed, substantially as set forth. 95

2. As a new article of manufacture, a snare- 100

string comprising a number of strings of fibrous material weatherproof, compressed, and having applied to its smooth outer surface a weatherproof covering, substantially as set forth.

3. As a new article of manufacture, a snare-string comprising a number of strings of fibrous material weatherproofed, compressed, and having applied to its smooth outer sur-

face a coating of shellac or other resinous material, substantially as set forth.

In testimony whereof I affix my signature in presence of two witnesses.

EMIL BOULANGER.
